UNITED STATES PATENT OFFICE.

CARL STENBOL, OF SAULT STE. MARIE, ONTARIO, CANADA.

WIDE-OPENING CLAM-SHELL BUCKET.

1,382,327.

Specification of Letters Patent. Patented June 21, 1921.

Application filed April 29, 1920. Serial No. 377,629.

To all whom it may concern:

Be it known that I, CARL STENBOL, a subject of the King of Great Britain, and resident of Sault Ste. Marie, in the Province 5 of Ontario, Dominion of Canada, have invented certain new and useful Improvements in Wide-Opening Clam-Shell Buckets, of which the following is a specification.

This invention relates to improvements in 10 ore buckets of the wide opening gravity clam type, having separate opening and closing ropes, and the objects of the invention are to provide a bucket of simplified design and have a greater digging capacity in proportion to its weight, in which the various 15 operative parts will be well designed to perform the functions required of them.

Further objects of the invention are to obtain uniform closing power and increased 20 traveling stability.

It consists essentially of the improved construction hereinafter described in detail in the accompanying specification and drawings:

25 In the drawings;

Figure 1 is a side elevation of an embodiment of the invention.

Fig. 2 is an end elevation.

Fig. 3 is a sectional plan taken on the line 30 $x-x$ of Fig. 1.

Fig. 4 is a sectional elevation of the bucket partly open.

Fig. 5 is a sectional detail on the line $y-y$ of Fig. 4.

35 Fig. 6 is a part section and part elevation of the top pulley supporting bracket.

Fig. 7 is a detail and side elevation of the closing sling and spool supporting the same.

Fig. 8 is a sectional detail and part elevation on the line $z-z$ of Fig. 7.

Fig. 9 is a detail elevation showing the supporting pin at the top of the bucket.

Fig. 10 is a detail elevation of one of the controlling links.

45 In the drawings, like characters of reference indicate corresponding parts in all the figures.

Referring to the drawings, A and B indicate the two bucket parts adapted to centrally abut when closed as shown in Fig. 1, both bucket parts being supported at their inner ends by pairs of pivot supporting arms C and D, which pairs of arms are pivoted together at their upper ends by suitable pivot pins 10.

The outer ends of the bucket parts A and

B are supported and controlled in an angular position by pairs of controlling links E and F, which are pivoted to suitable brackets 11 and 12 on the bucket parts, the upper ends of the links E and F being pivoted to toggle levers G and H.

The inner ends of the toggle levers G and H are pivoted together by a suitable pivot pin 13, while the outer ends are pivoted to 65 the arms C and D by pivot pins 14 and 15, which may be surrounded with suitable sleeves 16 and 17 each formed with end flanges 18 designed to bear against the sides of the levers and give increased support 70 thereto.

Movement of the toggle levers G and H is effected by means of opening ropes 19 and 20, which extend through a fixed pin 21 on a bracket 22 mounted on the pivot pin 75 10, around separate spools 23 and 24 mounted freely on the pin 13 provided on the lower side with a semi-circular guard 25, the opening ropes extending in a manner well known in the art over pulleys 41 to a suitable winding drum or other mechanism for operating the same.

It will be seen that as the opening ropes are operated, the pivot pins 13 will be raised, opening the arms C and D as shown in Fig. 85 4, and causing the upper pivot pins of the levers E and F to swing inwardly rocking the bucket parts about the pivot points of the levers C and D.

The closing mechanism will now be described, and includes closing ropes 26 and 27, which extend around pulleys 28 and 29 on the bracket 22, and at the inner ends are wound around and connected to drums 30 and 31, which are mounted on transversely 95 extending spools 32 and 33, which spools are mounted on suitable shafts 34 and 35, supported from the pairs of arms C and D.

The spools turn with the drum and the spools have closing slings 36 and 37 connected thereto, each closing sling having one end connected to a pin 38 on one of the arms C or D, while the other end of the sling is wound around and secured at its end to the opposite spool. In this way when a pull 105 is exerted on the closing ropes, the drums are turned, and the turning of the drums, wind up the slings 36 and 37, drawing the spools centrally toward each other, and carrying the pairs of arms C and D centrally 110 toward each other, and thus closing the bucket parts A and B.

The method of attaching the closing slings to the spools is particularly to be noted. Each sling extends through eyes 37^a formed in rings 37^b which extend around the spools 5 32, the eye being formed in part by the ring and in part by depressions 37^c in the spool 32.

The eye is formed with rounded edges so that the sling may slide in it. Eyes 37^a are 10 spliced in opposite ends of the sling, which eyes are attached to either pair of the arms C or D.

It will be seen that this arrangement constrains the uniform strain on opposite sides 15 of the slings.

To give additional strength to the arms C and D, angle bar braces or members 40 are provided thereon, which also act as guards preventing the bucket from catching with 20 projecting nuts, etc., when going through openings such as the hatchway in a boat.

To give additional brace to the levers E and F in closed position and to limit their movement, cross bars 39 are provided connecting the members of each pair of links 25 E or F. The sides of which are suitably secured to the bucket parts. The bucket members A and B may be reinforced also with members 39^a.

30 It will be seen that the mechanism for opening and closing the bucket parts has already been explained. It will be seen that it is constructed of few and simple parts. Attention is drawn to the top construction 35 of the bucket, which is such that in closing in sidewise the main arms C and D form a pointed or pyramid top, which greatly increases the bucket clearance when hoisting through a narrow opening such as the hatch 40 of a boat.

It will be observed that at the top, the pairs of arms C or D are bent inwardly in a lateral direction toward each other to effect economy in space as above indicated.

45 As many changes could be made in the above construction, and many apparently widely different embodiments of my invention, within the scope of the claims, constructed without departing from the spirit 50 or scope thereof, it is intended that all matter contained in the accompanying specification and drawings shall be interpreted as illustrative and not in a limiting sense.

What I claim as my invention is:

55 1. In a bucket of the character described and in combination, two bucket parts, sup-

porting arms pivoted together and to the bucket parts, toggle levers pivoted to the supporting arms, links connecting the toggle arms with the bucket parts, an opening rope 60 operatively connected to the end of the toggle levers, spools carried by the supporting arms, drums on the spools, and slings extending between the spools on opposite supporting arms in such a way that when the 65 spools are turned, the arms will be drawn closer together, and closing ropes operatively connected to the drums and adapted when pulled to turn the drums and spools and cause the slings to draw the supporting arms 70 together.

2. In combination, the arrangement according to claim 1, with a trolley having pulleys thereon, connected to the opening and closing ropes, in such a way that the 75 opening and closing ropes diverge centrally from the top of the bucket to the trolley.

3. The arrangement according to claim 1, in which connecting links are provided between the toggle arms and the bucket parts, 80 and in which cross bars are provided to limit the movement of the links.

4. The arrangement according to claim 1, in which the pairs of supporting arms are tapered toward each other, at the top and 85 connected by a pivot pin.

5. The arrangement according to claim 4, in which the pivot pin carries a bracket having pulleys thereon, over which the opening and closing ropes run.

6. The bucket of claim 1, in which the main supporting arms are bent inwardly in a lateral direction at the top.

7. The arrangement according to claim 1, in which the slings are connected to the 95 drum by means which permit automatic adjustment of the length on opposite ends of the slings.

8. The bucket according to claim 1, in which the slings are connected to the spools by rings having eyelets therein, through 100 which the slings are automatically adjusted.

9. The arrangement according to claim 1, in which the supporting arms have protecting angle members 40 thereon.

In witness whereof I have hereunto set my hand in the presence of two witnesses.

CARL STENBOL.

Witnesses:

C. A. MAENS,
E. S. M. ESSEN.
